DESIGN.

R. W. HARDIE.

AIR MOISTENER.

APPLICATION FILED SEPT. 25, 1916.

50,019.

Patented Dec. 12, 1916.

R. W. Hardie Inventor

UNITED STATES PATENT OFFICE.

ROBERT W. HARDIE, OF MOUNT VERNON, NEW YORK.

DESIGN FOR AN AIR-MOISTENER.

50,019.

Specification for Design.

Patented Dec. 12, 1916.

Application filed September 25, 1916. Serial No. 122,162. Term of patent 14 years.

To all whom it may concern:

Be it known that I, ROBERT W. HARDIE, a citizen of the United States, and resident of Mount Vernon, in the county of Westchester and State of New York, have invented a new, original, and ornamental Design for Air-Moisteners, of which the following is a specification, reference being had to the accompanying drawings, forming a part thereof.

The figure is a perspective view of an air moistener showing my new design.

I claim,

The ornamental design for an air moistener substantially as shown.

ROBERT W. HARDIE.

Witnesses:

JAMES A. STANCHFIELD,
JOHN F. DERY.
